TEETH CLEANING AND GUM MASSAGING
DEVICEFrances I. Lynch, Yonkers, N. Y., assignor to In-
dex Finger Tooth Brush, Inc., New York, N. Y.,
a corporation of New York

Application March 30, 1936, Serial No. 71,712

5 Claims. (Cl. 128—62)

This invention relates to a device for cleaning and conditioning teeth and gums, and more particularly to a rubber cot having surface appliances adapted for teeth cleaning and gum massaging operations.

In the development of scientific information regarding the care of the teeth, it has been ascertained that the health of the teeth structure is closely associated with that of the gums, so that any treatment of teeth to maintain their normal vigor and perfection should be associated with a coincident treatment of the gums to insure adequate blood supply and firm supporting tissue for the teeth. Heretofore it has been customary to supply devices such as bristle tooth brushes which are limited only to a brushing operation on the teeth, there being no provision for adequate gum treatment.

It is an important object of the present invention to provide an oral appliance which may be used in sequence as a comprehensive tooth cleanser as well as a massage device. Another object of the invention is to provide a tooth cleanser and conditioner which is susceptible of use on tender gums without irritation thereto. A further object is to provide a device of this type which permits a graduated pressure treatment for the gums to bring them into proper condition. Still another object is to provide a device of the type indicated which may be employed in the plural operations of teeth cleaning, teeth polishing and gum massaging. An object also is to provide a tooth appliance which may be cleansed in accordance with surgical requirements. Still another object is to provide a dental appliance which supplies a plural cleaning means adapted to reach varying depths of interdental cavities. Further objects will be apparent on consideration of the following description and of the accompanying drawing, in which:

Fig. 1 is an enlarged elevational front view of the cleaning and massage device showing a single row of long projections;

Fig. 2 is a transverse sectional view taken on line 2 of Fig. 1;

Fig. 3 is a back elevational view of Fig. 1 showing the angular ridges;

Fig. 4 is a longitudinal section on line 4—4 of Fig. 3;

Fig. 5 is a transverse sectional view showing one method of using the device;

Fig. 6 is a front elevational view of a modification showing long projections in a double row at the end of the cot and a single row on the sides;

Fig. 7 is a transverse sectional view taken on line 7—7 of Fig. 6;

Fig. 8 is a back elevation of Fig. 6 showing spaced longitudinal projections and spaced ridges;

Fig. 9 is a longitudinal section of another modification similar to Fig. 4 but with long projections interspersed with short ones; and

Fig. 10 is a transverse sectional view taken on line 10—10 of Fig. 9.

In Fig. 1, I have illustrated a form of my invention which may be preferred and which consists of a rubber stall or cot 10 adapted to be positioned preferably on the index finger of the hand, there being provided to assist positioning 15 and removal of the cot the end flaps 11 and 12 at the open end of the cot. The cot has two main surfaces, the front surface 13 and the rear surface 14. On the front surface is formed a plurality of projections 15 and 16, the projections 15 being approximately one-eighth inch in length, and the projections 16 being somewhat larger, as clearly indicated in Fig. 1. As shown also in this figure, the projections 15 are dispersed preferably regularly over the cot surface 13, the enlarged projections 16 forming an outer boundary 20 extending along the sides and outer end of the cot enclosing the area of lesser projections 15 on three sides. The projections 15 and 16 are of rubber and are integral with the cot surface, 25 and since the rubber employed is of a flexible nature both the cot surface and the projections are susceptible to resilient displacement when subjected to pressure against a harder material such as a tooth or gum surface. To increase 30 slightly the resistance to deformation the various projections are approximately conical in contour and terminate in a dull point.

On the rear face 14 of the cot the surface is free of projections except for a banded area 9 40 extending angularly over this surface from the rear to the front of the cot, thus leaving a smooth, unbanded area 8 on the front end of the rear surface. The banded area includes a plurality of slightly projecting strips 17 and 18 having 45 rounded edges, the strip 17 forming the forward edge of the banded area 9, and the strip 18 forming the rear edge. Intermediate the two strips 17 and 18 are a series of aligned circular protuberances 19 having flat top areas, the height 50 of these protuberances and that of the strips 17 and 18 being approximately the same. An aperture 20 is formed in the end of the cot to permit movement of air in conjunction with the insertion or removal of the finger from the cot.

In using the cot as described and as shown in Figs. 1 to 5 inclusive, the cot is placed preferably on the forefinger with the front face of the cot over the inside of the finger. If it is desired to utilize cleaning agents such as tooth powder or paste or medicaments, these may then be applied to the prejections and the cot then placed over the tooth surface. The brushing action should be from the gum toward the distal surfaces, in which movement the projections ride over the sides of the teeth and in the inter-dental cavities. The action is both frictional and sweeping, the soft surfaces of the rubber exerting a complete cleaning action, removing not only film and bacterial plaques by frictional contact, but also removing inter-tooth food particles in a series of sweeping movements of the various transversely positioned projections. The small projections remove the ordinary particle accumulation but their action is facilitated by the provision of the outer row of enlarged projections 16 which insures complete removal of food particles between teeth of greatly varied arrangement and depth of inter-dental cavities. Fig. 5 illustrates the action of the projections on and between the teeth.

Having completed the cleaning operation by subjecting the teeth to this sweeping action along all of the tooth surfaces, the gums may then be subjected to treatment both for cleaning and stimulating the flow of blood in the gum tissue. In the gum conditioning operation the treatment will depend somewhat upon the sensitivity of the gums, as well as the prior methods of treatment. Where the gum is more or less tender or irritated due to bristle irritation or to diseased conditions or lack of proper treatment, the initial operation should be with the bristles where, guided by the tactile sense of the finger, a light circular motion is imparted to the cot, moving the projection terminals over the gum surface with a minimum of pressure. If the gum tissue is healthy and normal this preliminary cleaning and stimulating step may be succeeded by the application of the projection surfaces of the rear side of the cot. The principle involved in the banded area of the rear surface of the cot is that of stimulation from alternate pressure and release of pressure, this being fundamental to the massage operation. The banded area succeeds in this stimulating effect when the cot is moved slowly in an axial direction, the ridges moving continuously over the surface of the gum. This brings about a wave-like pressure effect which passes over the gum succeeded by an immediate release of pressure, this occurring in quick succession as the pressure from strip 18, for example, is succeeded by the pressure of the protuberances 19 and the succeeding strip 17. The strips 17 and 18 produce a uniform pressure over the gum area as the cot is moved, whereas the protuberances 19 produce an intermittent or broken pressure approximately transverse to their direction of movement. The angularity of the strips tend to cause a sweeping movement from the upper to the lower part of the gum, when moved in a direction away from the closed cot end, which is advantageous where there is an unhealthy condition of the tooth base, and thus assisting in the elimination of detrimental secretions. The treatment of the banded area may be preceded by a simple pressure operation resulting from application of the smooth area 8 of the cot on the gum surface. This area is particularly use-

ful in the dental treatment of children or teething babies.

In Fig. 6 I have shown a modification of the structure of Fig. 1, this modification differing over the previously described form by the inclusion of a second row 25 of enlarged projections at the outer end of the cot, the projections 15 and 16 being as in the first disclosure. The object of the added row of large projections 25 in this modified structure is to facilitate tooth cleaning where special difficulty is found in the removal of food particles, the use of the cot in this connection being with an end movement instead of side movement. After using the end projections, the usual side sweep of the cot may be employed in the cleaning action.

In the modification of Fig. 6 I employ an alternative form of massage or conditioning surface on the rear face 21 of the cot which comprises a plurality of parallel and axially positioned ridges 28 having rounded surfaces together with circular protuberances 29 aligned in extension of each ridge. The utility of this form of gum conditioning surfacing will appear from the fact that as the cot travels axially over the gum the pressure is concentrated in the ridges 28, but since this is a moving pressure for any given point in the gum surface there will be a continuous pressure for a longer time interval followed by intermittent short time pressures as the protuberances 29 move over the point. This pressure on the gum, intermittent as to duration and variable as to point of application, is found to have a pronouncedly stimulating effect on the gum tissue and forms an effective aid to maintaining the health of teeth and gums. In this arrangement also there is provided the open and smooth surface 30 for sensitive gum treatment.

In the modification of Fig. 9 I have illustrated a cot in which the short projections 35 and the long projections 36 are positioned in alternative rows around the front surface 37 of the cot so that both size projections are effective throughout the teeth cleaning operation. In this modification the rear surface 38 of the cot is free of protuberances or ridges and it is employed for massage or conditioning operations simply as a pressure element.

In all of the modifications mentioned the rear face of the cot is adapted for use as a polishing means for the teeth as well as for its normal use of gum conditioning succeeding the teeth brushing operation in conjunction with the projections on the front face of the cot. The rear face of the cot lends itself particularly to pressure, whereas the front face of the cot is adapted for treatment where less pressure is desirable, but it is apparent that both the projection surface of the cot as well as the ridge surface are capable of imparting a frictional action on the teeth whereby either with or without added polishing substances the surface of the teeth may be polished.

In all modifications, also, a smooth area as at 3 of Fig. 3 is provided suitable for massage on tender surfaces or for tooth polishing.

While projections of two groups as to length have been described, I may employ additional groups to serve specific effects.

In treating the teeth with the appliances as above described it is desirable that the sequence of operation suggested be followed, such as the preliminary sweeping operation followed by the projection gum treatment, and concluding with the pressure massaging with the rear face of the

cot. By this means the teeth and the associated gums are cleaned and properly conditioned so as to be maintained in a normally healthy condition.

Modifications other than herein shown and described may of course be made, hence applicant does not desire to be limited except as required by the scope of the claims hereto appended.

I claim as my invention:

1. A dental conditioning device comprising a cot having a front face with a plurality of yieldable projections only thereon and a rear face having plural ridges thereon extending in an acute angle thereon with reference to the cot axis, and a plurality of protuberances formed between said ridges.

2. A dental conditioning device comprising a flexible cot, a plurality of projections having a length of one-eighth inch or less, and a plurality of similar projections having a length in excess of one-eighth inch, said projections covering the front surface area of said cot and extending radially therefrom.

3. A dental conditioning appliance comprising

a flexible cot, a plurality of pointed projections having a uniform length on the front face of the cot, a plurality of pointed projections of a length greater than that of the first mentioned pointed projections forming a fringe about the area covered by the first mentioned projections, and a gum massaging area on the rear face of the cot.

4. A dental conditioning device comprising a cot having a front and rear face, the front face being provided with a plurality of resilient pointed projections, some of which having a length differing from others, and the rear face being provided with a plurality of ridges whereby the teeth and gums may be subjected to a sequential cleaning, massaging and polishing operation.

5. A dental conditioning device comprising a flexible cot, and two groups of resilient projections formed radially on the surface of said cot, the length of the projections in each group being of equal size, the size differing between the groups.
